UNITED STATES PATENT OFFICE.

FREDERICK H. CASEY, OF GARDNER, MASSACHUSETTS.

INKSTAND.

1,260,870.

Specification of Letters Patent. Patented Mar. 26, 1918.

Application filed August 10, 1915. Serial No. 44,785.

To all whom it may concern:

Be it known that I, FREDERICK H. CASEY, a citizen of Canada, residing at Gardner, in the county of Worcester and State of Massachusetts, have invented new and useful Improvements in Inkstands, of which the following is a specification.

This invention relates to ink stands, and it has particular reference to that class of ink stands which are equipped with a well communicating with a source of supply of such a nature that the ink in the well will be maintained at a constant level.

The object of the invention is to produce an ink stand of this class in which the channel or duct whereby the well communicates with the source of supply will be so arranged as to constitute an air inlet which will always be open for the passage of air to replace the ink drawn from the source of supply.

A further object of the invention is to simplify and improve the valve whereby the reservoir constituting the source of supply communicates with the duct and through the latter with the well.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of the invention, it being, however, understood that no limitation is necessarily made to the precise structural details therein exhibited, but that changes, alterations and modifications within the scope of the claim may be resorted to when desired.

In the drawing,—

Figure 1 is a top plan view of an ink stand constructed in accordance with the invention.

Fig. 2 is a vertical sectional view taken on the line 2—2 in Fig. 1.

Fig. 3 is a view in side elevation of the reservoir that constitutes the source of supply.

Fig. 4 is a sectional detail view, enlarged, of the valve and valve casing.

Fig. 5 is a sectional detail view taken on the line 5—5 in Fig. 1.

Corresponding parts in the several figures are denoted by like characters of reference.

The body 15 of the improved ink stand may be constructed of glass or other suitable material, and it consists of a block of substantially rectangular shape having near one end thereof a recess 16 constituting the well and near the other end a relatively shallow recess 17, the lower end or bottom portion of which communicates with the well through a duct or passage 18 which latter terminates at a distance above the bottom of the well 16. The duct 18 is preferably quite narrow, but of relatively great height, as will be best seen in Fig. 5 of the drawing.

The reservoir which has been shown at 19 is in the nature of a bottle or receptacle having a short neck 20 which has been shown as being externally threaded for the reception of a tightly fitting cap 21 through which extends a tube 22 having at one end a port or seat 23 for a spring actuated valve 24 carried by a stem 25 which is surrounded by the coiled actuating spring 26, one end of the latter abutting on the valve and the other end on an inturned flange 27 of the tube 22. The stem 25 is made to project beyond the ported seat 23, as will be seen in the figures of the drawing. The projection of the tubular housing into the reservoir is an important feature as it prevents the draining of all the ink from the reservoir. The dregs or sediment will remain in the neck of the reservoir around the casing and will not pass into the casing. Clogging of the passages is thus prevented.

In assembling the parts the cap 20 is applied to the receptacle 19 with the valved portion projecting outwardly therefrom, so that the receptacle may be inverted without spilling the ink. The receptacle is then placed on the body portion of the stand with the neck 20 extending within the recess 17, the parts being so arranged that when the receptacle is thus applied the projecting end of the valve stem will impinge on the bottom portion of the recess 17, thereby forcing the valve against the tension of the spring 26 sufficiently to permit the ink to flow through the tube 22. As the ink flows it will be replaced by air entering through the duct 18, which latter is so proportioned and arranged with respect to the valved tube 22 that the valved portion of the latter will be positioned below the top wall of the duct. It follows that when the level of the ink reaches the mouth of the valved tube, there

by stopping the flow, an air passage will still exist between the ink in the duct 18 and the upper wall portion of said duct, thus permitting air to freely enter through the 5 well and duct as the level is lowered in the well by use, evaporation or other causes. To prevent undue evaporation a swinging cover 28 is provided.

The improved ink stand, as will be seen 10 from the foregoing description, is capable of being produced at a moderate expense.

Having thus described the invention, what is claimed as new, is:—

In an inkstand of the class described, the 15 combination with a base member having a shallow recess, a relatively deep well, and a duct communicating at one end with the shallow recess and at the other end with the well above the bottom of the latter, of a 20 reservoir having a short neck, a cap tightly fitting said neck, a tubular housing extending through the cap and into said reservoir

the length of the neck and having a ported seat at its outer end and an inturned flange at its inner end, a stem extending through 25 the tube and having a valve housed therein and engaging the seat, and a spring coiled about the stem within the housing between the valve and the inturned flange; the neck of the reservoir being adapted to be disposed within the shallow recess in the base and the outwardly projecting end of the valve stem being adapted to engage the bottom of said recess to unseat the valve, the extension of said tubular housing into 30 said reservoir preventing the draining of sediment from the reservoir into the valve housing.

In testimony whereof I affix my signature in presence of two witnesses.

FREDERICK H. CASEY.
